(57) **CLAIM**

The ornamental design for an electric stand-up scooter, as shown and described.

DESCRIPTION

FIG. 1 is a front perspective view of the electric stand-up scooter of my new design;

FIG. 2 is a side view of the electric stand-up scooter of FIG. 1, as seen from the right side of FIG. 4;

FIG. 3 is a side view of the electric stand-up scooter of FIG. 1, as seen from the left side of FIG. 4;

FIG. 4 is a front view of the electric stand-up scooter of FIG. 1;

FIG. 5 is a back view of the electric stand-up scooter of FIG. 1;

FIG. 6 is a top view of the electric stand-up scooter of FIG. 1; and,

FIG. 7 is a bottom view of the electric stand-up scooter of FIG. 1.

The broken lines are for the purpose of illustrating portions of the electric stand-up scooter that form no part of the claimed design.
